UNITED STATES PATENT OFFICE.

JOSEPH G. THORNE, OF BARNUM, MINNESOTA.

DOOR FASTENER.

Application filed September 24, 1926. Serial No. 137,551.

This invention relates to fasteners and more particularly to a fastener adapted to be applied to a swinging door employed in connection with a building or vehicle to close the doorway thereof.

One object of the invention is to provide a fastener which, when the door is closed, will serve to hold the door shut and prevent it from rattling.

10 Another object of the invention is to permit the casing of the fastener to be readily secured to the door and the keeper-engaging member operated from either side of the door.

15 Another object of the invention is to so form the keeper-engaging member that, when projected and engaged with the keeper, a cam action will occur and cause the door to be firmly held shut and prevented from 20 rattling.

Another object of the invention is to so mount the keeper that it may be adjusted and compensate for wear.

The invention is illustrated in the accompanying drawing, wherein

Figure 1 is a view showing the improved fastener applied to a door and door frame, the view being partially in vertical section and partially in elevation;

30 Fig. 2 is a vertical sectional view taken on the line 2—2 of Fig. 1;

Fig. 3 is an edge view of the keeper-engaging member, and

Fig. 4 is a fragmentary sectional view 35 taken on the line 4—4 of Fig. 1.

The door fastener constituting the subject-matter of this invention includes a casing 1 preferably formed of metal and having a side wall 2 from which extend marginal walls 3, 4 and 5. A second side wall 6 fits against the free edges of the marginal walls and is secured by bolts 7 which are preferably of sufficient length to extend through the door 8 to which the casing is to be secured.

45 It will be obvious, however, that the wall 6 could be secured to the door by screws or bolts and the body of the casing consisting of the wall 2 and marginal walls attached to the wall 6 by bolts or in any other desired manner.

A turning shaft 9 extends through aligned openings 10 and 11 in the walls 6 and 2 and is of sufficient length to project through the door and from opposite sides thereof if the 55 casing is mounted in a pocket cut in the body of the door instead of being attached to one

face thereof, as shown in Fig. 1. Handles 12 are provided at the ends of the operating shaft so that it may be easily rotated when actuation of the fastener is necessary. The keeper-engaging member 13 which is normally disposed within the casing 1 consists of a substantially semi-circular disk formed of strong metal and provided with a hollow hub 14 adapted to fit snugly upon the operating shaft. A set screw 15 is passed through a threaded opening formed in the hub and adapted to frictionally engage the shaft and firmly hold the keeper-engaging member in a set position. By referring to Fig. 2 it will be seen that the casing carries an abutment pin 16 which is preferably in the form of a removable bolt or screw and is located adjacent the lower end of the casing so that it may be engaged by the keeper-engaging member and limit movement thereof when projected from the casing or swung into it. The face 17 of the keeper-engaging disk extends in a single plane throughout its area and the opposite face has a portion 18 disposed parallel to the face 17 to provide a neutral surface and for the remainder of its area converges toward the face 17 in the direction of the opposite end of the disk to provide a cam surface 19. It will thus be seen that, when the securing disk is viewed as shown in Fig. 3, it gradually increases in thickness from its lower end toward its upper end where the cam surface 19 merges into the neutral surface 18 which extends to the upper end of the disk.

The keeper plate 20 which is secured against one side of the door frame 21 is formed of metal and adjacent its outer side edge is provided with a longitudinally extending slot 22 through which the keeper-engaging member or disk 13 passes into a socket 23 formed in the door frame. Slots 24 are formed transversely in the keeper plate adjacent its upper and lower edges and are provided with inwardly converging upper and lower edge walls, one or both of which will be serrated to form rack teeth 25. Screws 26 are passed through the slots 24 and carry wedging blocks 27 formed with teeth 28 to interlock with the teeth 25. By referring to Figs. 1 and 4, it will be seen that by loosening the screws 26 the blocks may be moved out of interlocking engagement with the keeper so that the keeper may be moved transversely in order to compensate for wear upon the outer edge wall of the slot 22.

or contacting face of the fastening disk 13.

When the fastener is in use, the casing is secured upon the door with the end portions of the shaft 9 projecting from opposite sides of the door. The keeper is secured against a side of the door frame and adjusted to such a position that the disk may enter the slot 22. By turning the handle after the door has been closed, the tapered end of the disk first enters the slot and as turning is continued the cam surface 19 through engagement with the outer edge wall of the slot 22 will force the door inwardly to a tightly closed position and rattling of the door will be prevented. Since the neutral surface which is parallel to the face 17 engages the outer wall of the slot 22 when the door is completely closed the disk will be prevented from slipping out of close contacting engagement with the keeper plate and since the disk engages the abutment pin 16 when swung to the operative position shown in Fig. 2, it may not be turned too far. If the outer edge wall of the slot 22 becomes worn, it is merely necessary to release the screws 26 and move the keeper plate inwardly a sufficient distance to compensate for the wear and then again tighten the screws. It will thus be seen that with this fastener a door of a building or vehicle, such as an automobile, may be firmly held closed and prevented from rattling. Movement of the securing disk in projecting and retracting directions is limited by its engagement with the abutment pin 16 and therefore it cannot be moved in either direction beyond the proper position. It should be also noted that when projected to the operative position the heaviest portion of the disk formed with the neutral surface 18 is moved outwardly over the top center to hold itself in the projected position and that when retracted its heaviest portion is disposed at its bottom and inwardly of the abutment pin and prevents the disk from having a tendency to turn outwardly. Therefore, the disk will retain itself in either a retracted or projected position and no springs or the like are required.

Having thus described the invention, I claim:

1. A keeper formed with a slot having a side wall converging inwardly toward an opposed side wall, and adjustable securing means for said keeper adapted to be passed through the slot and engaged with a support with a portion fitting into said slot and bearing against the opposed walls of the slot to releasably secure the keeper in a set position but permit adjustment of the keeper longitudinally of the slot when the securing means is loosened.

2. A keeper formed with a slot having in-

wardly converging side walls, one wall being provided with teeth and securing means 65 for said keeper adapted to be passed through the slot and engaged with a support with a portion fitting into said slot and formed with beveled side faces bearing against the converging walls of the slot to releasably 70 secure the keeper in a set position, one side face of the securing means having teeth to interlock with the teeth of the slot wall.

3. A keeper formed with a slot having a side wall converging inwardly towards an 75 opposed side wall and provided with teeth, a retainer fitting into said slot and having opposed side edge faces engaging the opposed walls of the slot, one edge face of the retainer being provided with teeth interengaging the teeth of the wall, and a fastener adapted to be passed through said retainer into a support and releasably hold the retainer in tight engagement with the opposed walls of the slot and releasably 80 secure the keeper in a set position.

4. A keeper formed with a slot having a side wall converging inwardly towards an opposed side wall, a block of less length 90 than said slot and formed with a fastener receiving opening fitting into the slot, and a fastener for said block adapted to be passed through the opening therein into a support and secure the block to the support with opposed edge faces of the block engaging the side walls of the slot to releasably secure the keeper against the support in a set position.

5. A keeper of the character described comprising a plate formed with fastener receiving slots, blocks adapted to fit into the fastener receiving slots and have wedging engagement with opposite walls thereof and slidably longitudinally therein to permit adjustment of the keeper longitudinally of the 100 slots, and screws adapted to be passed through openings in the blocks into a support to releasably secure said blocks in binding engagement with the opposed walls of the slots.

6. A keeper for a door fastener comprising a plate to fit against a support and formed with fastener receiving slots, blocks adapted to fit into the fastener receiving slots and have wedging engagement with opposite walls thereof and slidably longitudinally therein to permit adjustment of the keeper longitudinally of the slots, the blocks and keeper having contacting edge faces serrated to provide interlocking teeth, and screws adapted to be passed through the blocks into the support and releasably secure said blocks with their teeth interlocked with the teeth of the keeper.

In testimony whereof I affix my signature.
JOSEPH G. THORNE. [L. s.]
